AIR CELL

Hardy H. Raulerson, Long Beach, Calif.

Application July 29, 1938, Serial No. 221,960.

3 Claims. (Cl. 103—224)

This invention relates to improvements in pump air cells.

The general object of the invention is to provide an improved air cell which in combination with a reciprocating pump insures a more nearly constant flow than is possible with former equipment.

Another object of the invention is to provide an air cell which may be sunk in a well and placed advantageously close to the piston.

Another object of the invention is to provide an air cell in which the air therein is automatically replenished.

Another object of the invention is to provide a novel pump construction wherein a plurality of air cells are employed.

Another object of the invention is to provide an air cell in which the air is replenished through a hollow sucker rod.

Other objects and advantages of my invention will be apparent from the following description taken in connection with the accompanying drawing, wherein:

Fig. 1 is a view of a pump wherein an air cell embodying the features of my invention is employed;

Fig. 2 is an enlarged vertical section of the air cell;

Fig. 3 is a section taken on line 3—3 Fig. 2;

Fig. 4 is a diagrammatic view showing a number of air cells in series; and

Fig. 5 is a vertical section showing a modified air cell.

Referring to the drawing by reference characters I have shown my invention as embodied in an air cell which is indicated generally at 10. As shown in Fig. 1 the air cell 10 is used in connection with an ordinary well 11, a double action pump 12, a well head assembly 14, a sucker rod 15 and a column 16.

The double action pump 12 is similar to the pump described in my co-pending application, Serial No. 183,817, filed January 7, 1938 and includes an outer barrel 12a, an inner barrel 12b, a piston 12c within the barrel 12b, upper inlet valves 13, a lower inlet valve 13a, an upper inner valve 13b, and a lower inner valve 13c. The piston 12c is operated by the sucker rod 15 and as the latter moves up and down the fluid is raised during each movement.

As shown in Fig. 2 the air cell 10 includes a hollow cylindrical body portion 17 having upper internal threads 18 and lower internal threads 19. A lower coupling 20 engages the threads 19 and an upper coupling 21 engages the threads

18. The coupling 21 has a reduced portion 22 with external threads 23 engaging the lower end of a collar 24 the upper end of which threadedly engages the lower end of the column 16. The coupling 20 has a reduced portion 25 having external threads 26 engaging the upper end of a collar 27 the lower end of which threadedly engages the pump cylinder 12.

The coupling 21 has a central bore 28 with a lower enlarged portion 29 and a further enlarged portion 30 therebelow. Within the enlarged portion 29 is positioned a hollow cylinder 31 coaxial with the body portion 17 and forming an annular chamber 32 therewith. The cylinder 31 is preferably secured to the coupling 21 as by welding and is further supported by a spider 33 having a central ring 34 engaging the cylinder 31 and a plurality of radial legs 35 engaging the body portion 17. The coupling 20 has a central bore 36 having an upper enlarged portion 37. The sucker rod 15 passes axially through the cell 10.

It will be seen that in operation the water or other fluid being pumped will rise through the hollow cylinder 17 and will partially fill the annular chamber 32, air or other gases being trapped therein. The gases will have a beneficial cushioning effect producing a constant flow of water, and being adjacent the pump cylinder 12 will be particularly effective in producing a smoothly performing pump.

The trapped air or gases will, however, in time be dissolved in the water or other fluid and will need to be replenished. To this end I provide conduit means connected to an automatically controlled supply of compressed air or other gases.

As shown in Figs. 1 and 2 a conduit 40 communicates with the chamber 32 through an aperture 41 in the coupling 21. The conduit 40 passes upwardly from the cell 10 through the well 11 and at its upper end is connected to a compressed air reservoir 42 through a control system 43. The reservoir 42 may be charged by an ordinary compressor 44 driven by suitable means such as an electric motor 45.

The control system 43 includes a pressure gauge 46, a pressure operated electrical switch 47 and an electrically operated valve 48. When the pressure within the chamber 32 drops below a predetermined limit, dependent upon the working head, the pressure operated switch 47 is closed which in turn opens the electrically operated valve 48 so the air or other gas is fed to the chamber 32 until the pressure in the chamber 32

is built up sufficiently to open the switch 47 and thus cause the valve 48 to be closed.

As shown diagrammatically in Fig. 4 a plurality of air cells 10' may be introduced into the column 16 at different depths being connected in series to the air supply conduit 40'. Reducing valves 49 are disposed between the cells 10' (except the lowest cell) and the conduit 40', as the pressure within each cell is a function of the depth, the lower cells requiring greater pressure than the upper. The cells in this arrangement would be used with an air reservoir 42' and a control valve 48' similar to the reservoir and valve previously described. The valve 48' is preferably operated by air pressure in the lowest cell.

In Fig. 5 I have shown a modification of my invention as embodied in a cell indicated generally at 50. The cell 50 includes a hollow cylindrical body portion 51, an upper coupling 52, and a lower coupling 53, these couplings being similar to the couplings previously described. Centrally positioned within the body 51 I provide a hollow cylinder 54 supported by spiders 55 similar to the spider 33. The cylinder 54 is longer than the pump stroke and has a gland 56 at the upper end thereof through which a hollow sucker rod 57 passes. The sucker rod 57 has radial apertures 58 opening therefrom into the interior of the cylinder 54. In operation the cell 50 is used in a well as is the cell 10, the fluid flowing through the annular passage between the body portion 51 and the cylinder 54, air being trapped within the cylinder 54 and replenished by means of the hollow sucker rod discharging through the apertures 58. The sucker rod 57 is connected by a flexible conduit 59 to a control system 60 similar to the control system 43.

From the foregoing description it will be apparent that I have invented new and useful improvements in air cells for pumps.

Having thus described my invention I claim:

1. In a pump construction having an elongated casing including a plurality of members, a sucker rod in said casing, said casing including a plurality of cells, said cell being distributed along said casing, each of said cells including an elongated body having a cylinder therein, said cylinder forming with the body a chamber which has a closed top portion and an open lower portion, said sucker rod passing through said casing and through said cylinders and means controlled by gas pressure in the lowest cylinder to supply gas under pressure to the upper portion of each of said cylinders.

2. In a pump construction having an elongated casing including a plurality of members, a sucker rod in said casing, said casing including a plurality of cells, said cells being distributed along said casing, each of said cells including an elongated body having a cylinder therein, said cylinder forming with the body a chamber which has a closed top portion and an open lower portion, said sucker rod passing through said casing and through said cylinders, means to supply gas under pressure to the upper portion of each of said cylinders, conduit means to supply gas to each of said cylinders including a source of fluid under pressure, a valve actuated by gas pressure in the lowest cell for controlling communication between said source and said cells and pressure reducing means associated between said conduit and all of said cells above the lowest cell.

3. In a pump including a casing, a sucker rod in the casing and means in the casing operated by said sucker rod for raising fluid, said casing having a plurality of air cells therein, each of said air cells including an outer body with a cylinder mounted in said outer body, the cylinders each engaging the outer body at the upper end and being free from engagement with the outer body at its lower end, said cylinders being spaced from said outer body to form an annular gas cell, said sucker rod being spaced from said cylinders, means adjacent the lower end of the cylinders and engaging the body to support the cylinders, conduit means communicating with the upper portion of each of the cylinders and adapted to supply gas under pressure to the cylinders, means to supply gas under pressure to the conduit means and valve means controlled by the pressure of gas in the lowest cell for controlling the flow of gas to each cylinder.

HARDY H. RAULERSON.
